UNITED STATES PATENT OFFICE.

JOSEPH H. POPE, OF HAMILTON, MASSACHUSETTS, ASSIGNOR TO UNITED SHOE MACHINERY COMPANY, OF PATERSON, NEW JERSEY, A CORPORATION OF NEW JERSEY.

LAST.

1,202,583.

Specification of Letters Patent.

Patented Oct. 24, 1916.

Application filed March 30, 1912. Serial No. 687,898.

To all whom it may concern:

Be it known that I, JOSEPH H. POPE, a citizen of the United States, residing at Hamilton, in the county of Essex and State 5 of Massachusetts, have invented certain Improvements in Lasts, of which the following description, in connection with the accompanying drawings, is a specification, like reference characters on the drawings indicating like parts in the several figures.

The invention relates to lasts which are used in the manufacture of shoes to support the materials for the shoes during the making thereof.

15 It is desirable in the manufacture of Goodyear welt shoes to support the materials for the shoes throughout the making and finishing operations. By this practice the last is subjected to a heavy crushing 20 pressure during the heelng operation. Notwithstanding the fact that numerous attempts have been made to strengthen the lasts to withstand the strains of the heelng operation this heavy pressure has a destructive action upon the last heelparts. It has 25 been proposed to separate the heelpart from the forepart while leaving the latter in position in the shoe so that the heel seat of the shoe could be placed over the post of a 30 heelng machine and the heelng operation performed without danger of injury to the last. Such lasts are so jointed that the heelpart of the last may be swung on the forepart to extend and collapse the last and the 35 heelpart separated from the forepart when desired. In order to separate the heelparts from the foreparts in these lasts it is necessary to move the heelpart rearwardly of the shoe resulting in the difficult removal of 40 the heelpart from the shoe or injury to the counter.

One of the objects of the present invention is to produce a last having a heelpart which may be readily separated from the 45 forepart and removed from the shoe without danger of injury to the counter.

To the accomplishment of this object a feature of the invention contemplates the provision, in a last provided with a forepart 50 and a heelpart, of a connection between the

fore and heel parts permitting the pivotal movement of the heelpart upon the forepart to collapse and extend the last and the separation of the heelpart from the forepart by a continuation of the collapsing pivotal movement of the heelpart beyond collapsed position. This construction obviates the necessity of moving the heelpart rearwardly of the shoe during the separating movement.

In the broader aspects of the invention the connection between the fore and heel parts may be formed in any suitable manner found desirable or expedient. In the preferred form of the invention the connection between the fore and heel parts takes the form of a coöperating pin and slot connection and this manner of connecting the fore and heel parts to permit the pivotal movement of the heelpart upon the forepart to collapse and extend the last and the separation of the heelpart from the forepart by a continuation of the collapsing pivotal movement of the heelpart beyond collapsed position forms an additional feature of the invention.

A further object of the present invention is to support the materials for a shoe during the making thereof so that the heelng operation may be performed while the shoe contains the last without injury thereto.

With this object in view a feature of the present invention contemplates the provision of a device for supporting the materials of a shoe during the making thereof consisting of a last provided with a projecting cylindrical socket and a post provided with a pin and a wall to enter and receive the socket respectively.

Broadly considered the last may be provided with a socket in any suitable manner. 90 In the preferred form of the invention the heelpart of the last consists of a heel shaped plate provided with a nail clenching surface upon one face and a cylindrical socket projecting from the other face. In order 95 that the counter of the shoe may be properly supported during the making and finishing operations the heel shaped plate is provided with a counter shaped wall rising from the peripheral edge of the plate, and the pin 100

socket is formed upon the plate within this wall. This construction forms another feature of the present invention.

In the accompanying drawings illustrating the invention in the best form now known to the inventor, Figure 1 is an inverted elevation, partly in section, of the last, forming part of the improved device for supporting the materials for a shoe during the making thereof; Fig. 2 is an inverted side elevation thereof showing the heel part in position to be detached from the last, and Fig. 3 is a perspective of a post employed with the last to support the materials of the 15 shoe during the heelng operation.

Referring now to the form of the invention illustrated in the drawings, a wooden forepart 1 is provided with a sloping vertical wall 2. This wall is bored to receive a 20 steel block 3 which is secured to the forepart so that its outer surface is flush with the wall 2. The block carries a transverse pin 4 and a tube 5 is arranged in a bore extending longitudinally of the last, and serves 25 to strengthen the forepart weakened by the removal of the wood.

The heelpart of the last is made of steel suitably pressed into the form illustrated in the drawings. As shown the heelpart consists of a heel-shaped plate 6 provided with a nail clenching surface 7 upon its lower face and with a cylindrical socket 8 projecting from its upper face. In order to support the rear of the shoe a counter shaped 35 wall 9 rises from the peripheral edge of the plate 6.

The plate 6 carries an arm 10 which extends beyond the straight edge of the plate so that its end may enter an opening 11 in 40 the block 3. The end of the arm 10 is formed as a slot 12 which hooks under the pin 4 so that the heelpart may swing upon the forepart to extend and collapse the last. In order to lock the last extended the end 45 of the arm 10 is provided with a groove 13 which, when the last is extended, is engaged by the head of a pin 14 loosely mounted in the tube 5. In order that the pin may automatically engage the groove as soon as the 50 last reaches extended position and be automatically disengaged therefrom when pressure is applied to the heelpart to collapse the last a spring 15 is coiled around the pin 14 and interposed between the head of the 55 pin and a screw 16 threaded into the end of the tube 5. When the last is moved into collapsed position the spring pressed pin 14 automatically engages the lower edge of the slot 12 (see Fig. 2) and locks the upright 60 collapsed heel part from returning to extended position under the influence of gravity. When it is desired to separate the heelpart from the forepart a continuation of the pivotal collapsing movement of the heel- 65 part beyond collapsed position causes the

arm 4 to swing out of engagement with the pin 4, thus permitting the heelpart to be removed without rearward movement of the heelpart toward the counter of the shoe. The provision of a pressed steel heelpart, 70 however, permits the heelng operation to be performed with the heelpart in the shoe without injury to the last. In order to support the heelpart firmly during the heelng operation the socket 8 receives a pin 17 75 formed upon a post 18, and the socket is in turn received within a wall 19 formed upon the post and spaced from the pin. The end of the wall 19 bears against the heel part around the base of the socket 8 and supports 80 the heel plate 6 against the thrust of the heelng machine. The end of the pin 17 also bears against the heel plate 6 and supports it, while the bottom of the slot 20 bears against and supports the rib 10. In order 85 to prevent the socket from turning upon the pin 17 the wall 19 is provided with a slot 20 which receives the arm 10. In order that the steel heelpart may properly hold the insole and the heelpart of the upper a wooden 90 tack receiving block 21 is inserted in the back of the wall 9 and also in the nail clenching surface 7.

The nature and scope of the present invention having been indicated and one form 95 having been specifically described, what is claimed as new is:—

1. A device for supporting the materials for a shoe during the making thereof consisting of a last provided with a projecting 100 cylindrical socket and a post provided with a pin and a wall to enter and receive the socket respectively, substantially as described.

2. A device for supporting the materials 105 for a shoe during the making thereof consisting of a last provided with a projecting cylindrical socket, a post provided with a pin and a wall to enter and receive the socket respectively and a coöperating arm 110 and slot connection between the last and the wall to prevent rotation of the last upon the pin, substantially as described.

3. A last having a heel part and a socket member projecting therefrom in combination with a support for said last comprising a pin shaped to enter said socket and a wall shaped to receive said socket and to support the heel-part at the base of said socket. 115

4. A device for supporting the materials 120 of a shoe during the making thereof comprising a last heel part having a projecting member, a rib on said projecting member, and a post provided with means for receiving said projecting member, and having a 125 slot for the reception of said rib, the bottom of said slot supporting said rib.

5. A device for supporting the materials 120 of a shoe during the making thereof comprising a last heel plate having a projecting 125

socket, an arm projecting from the wall of said socket, and a post having a pin and a wall to enter and receive said socket respectively, and a slot to receive said arm, 5 the bottom of the slot supporting said arm, and the pin and wall supporting the heel plate.

In testimony whereof I have signed my name to this specification in the presence of two subscribing witnesses.

JOSEPH H. POPE.
